BOILER FEED CONTROL

Julian A. Campbell, Long Beach, Calif.

Application January 10, 1940, Serial No. 313,234

15 Claims. (Cl. 122—451.1)

This invention has to do generally with apparatus for controlling the level of heated liquid in a chamber by regulation of the liquid feed thereto in accordance with changes in the liquid level, and is concerned particularly with an improved feed water control for steam boilers, designed to be less affected than ordinary regulators of this type by abnormal conditions such as sudden and wide variations in the boiler water level, and to be capable of maintaining a more constant water level under normal conditions.

The invention may be further characterized as pertaining to improvements in regulators of the type disclosed in my copending application Serial Number 220,719, filed July 22, 1938, now Patent Number 2,207,214 on Boiler feed water control, and comprising as the principal control element an inclined and longitudinally expansible metal tube connected at its upper and lower ends to the steam and water spaces, respectively, of the boiler so that the water stands in the tube at a level intermediate its ends and corresponding substantially to the water level in the boiler. As that level varies, the tube longitudinally expands or contracts and operates the boiler feed water control valve through suitable connections therewith. As will be understood, the present type of regulator is adaptable for water level control of boilers in general. It has proven particularly satisfactory for the control of feed water to oil field boilers, and may be described typically by reference thereto since the boilers used in drilling a well present some of the most difficult conditions to be encountered in liquid level control.

In well drilling operations, when elevating the pipe string from the hole the steam powered draw-works is run at practically full speed and the resultant rapid draw-off of steam from the boiler drops the pressure, which in turn causes the usual automatic fuel control to more intensely fire the boiler. This rapid increase in heating produces expansion in the boiler water due to the large formation of steam bubbles being released into the water from the heating surfaces below the water level. This expansion of the water may be observed by the rise of the water level in the gauge glass. This condition is momentary, however, because the rapid generation and release of steam soon builds up the pressure, causing the firing to be reduced and the water level in the boiler to lower. Elevation of the boiler water level is accompanied by a rise of water in the inclined regulator tube, and by reason of the tube being inclined, a relatively

small rise of the water level will run the water a much longer distance along the tube. For example, in some instances, a one inch water rise may run the water 12 inches along the tube.

The resultant cooling of the tube may be sufficient to entirely or partially close the feed water valve, and with the cooling effect of the feed water entering the boiler entirely or greatly cut off, both the liberation of steam and consequent expansion of the boiler water are much greater. The resulting high water level is of course conducive to wet steam and unnecessarily high fuel consumption. Only a relatively short period of time is required to elevate the drill pipe string, the length of one pipe stand, i. e. the length of section to be disconnected in each successive operation. While each stand of pipe is being unscrewed and landed on the derrick floor or a hanger, and while the elevator is being lowered to engage the next pipe stand, practically no steam is required, the boiler fires are low and the water settles back and runs down the controller tube, only to surge up again when the pipe string is again elevated. This repeated surging of water in the controller tube, tends to cause the water to be excessively heated due to the fact that heat is supplied to the tube by the surging water faster than radiation can cool the tube, and consequently the feed control valve will open more than is desirable, and an excessively high water level will occur in the boiler.

One of the primary objects of the invention is to cool the controller tube, preferably automatically in accordance with the rise and fall of the boiler water level, so that the tube is given a delayed sensitivity rendering its operation less affected by relatively rapid surges of the water, and at the same time impart to the tube greater sensitivity under normal operating conditions. In its preferred form, the invention contemplates cooling the tube and controlling the degree of cooling automatically by the rise and fall of the boiler water level, so that a falling level reduces the cooling and a rising level increases it. Generally speaking, these objectives are accomplished by applying a cooling fluid, preferably boiler feed water, to an upper portion of the controller tube above the normal water level therein, and regulating the rate at which the cooling fluid is applied to the tube in accordance with movements of the feed water valve, and therefore in accordance with changes in the boiler water level.

Preferably a constantly flowing stream of cooling water is applied to the controller tube, and

the flow of this stream is regulated to produce increased heating or cooling of the tube, as may be required in accordance with variations in the boiler water level. When through increased firing the water level drops in the controller tube and the resultant heating of the tube causes the feed valve to open, the cooling water flow to the tube is reduced so that the tube is permitted to heat sufficiently to slightly open the feed valve, all in a manner such that the water is raised to its proper level and a balance is established in the operation of the tube, feed water and cooling water control, to maintain that level. Sudden or spontaneous responsiveness of the regulator to surging of the boiler water, and the resultant difficulties ordinarily encountered, are obviated in that the tube has delayed action and its responsiveness is stabilized. This delayed action results from maintaining in contact with the tube a stream of cooling water that in effect increases the total specific heat of the tube and thereby introduces a time element in changing the temperature of the tube and causing the tube to influence the feed water control valve. This effect may be further increased by using an extra heavy tube, say of red brass or in some instances stainless steel, which promotes delayed action through retarding the heat transmission. As a result of these effects, the cycle of temperature changes of the tube is extended over a sufficient length of time to overcome the effect of water surge, and yet under all normal conditions, the controller has extreme sensitivity that will prevent any appreciable change in the water level.

The various objects and features of the invention discussed in the foregoing, as well as additional details, will be better understood from the following description of the invention as embodied in certain typical and illustrative forms. Throughout the description reference is had to the accompanying drawings in which:

Fig. 1 is an elevation view showing the regulator assembly and its connections with the feed water control valve;

Fig. 2 is a sectional enlargement of the feed water valve and the associated valve controlling the flow of cooling water to the regulator tube;

Figure 3 is an enlarged fragmentary section on line 3-3 of Fig. 1;

Fig. 4 is a view illustrating a variational means for applying a cooling fluid to the upper portion of the inclined regulator tube; and

Fig. 5 is a view similar to Fig. 4 illustrating a further variational form.

The regulator assembly generally indicated at 10 in Fig. 1, is shown to be connected to and to control valve 11 in the feed water supply line 12 leading to the boiler, the wall of which is conventionally indicated at 13. As will be understood, the showing of the boiler is merely conventional since the regulator is adaptable for controlling the water level in boilers of various types and designs. For the purpose of explaining the invention, it will suffice to refer to the regulator 10 as being so positioned with relation to the normal water level L of the boiler as to enable the regulator to operate the valve 11 in response to variations in the water level, all as will be fully explained hereinafter. While the invention is applicable to various type of regulators embodying an inclined tube within which the water stands at a level intermediate the upper and lower ends of the tube, I have shown for the purpose of explaining the invention, a form of regulator that may be regarded as typical and preferred. This

regulator 10 may be described generally as comprising a pair of elongated convergent members 14 and 15 interconnected at their outer ends by a casting 16 or other suitable means, and pivotally mounted at their divergent ends on a stationary support 17. Member 15 comprises an inclined tube made of suitable material, such as brass or for some purposes a proper grade and quality of steel, having a predetermined coefficient of expansion. The lower end of the tube is connected with the water chamber of the boiler by pipe 18 extending to the forward end 13a of the boiler and connecting into the lower end of the gauge glass 19 having the usual valved connections 21 and 20 with the boiler chamber above and below the normal liquid level L. Tube 15 is positioned at an elevation such that normally the boiler water stands in the tube at a level L located substantially at the longitudinal center of the tube.

The tube 15 is pivotally connected to the support 17 by a casting 22 attached to the web 17a of the support by bolt 23. Member 14 may be of any suitable form, and is shown typically as comprising a solid forked steel rod pivotally attached at 24 to the support 17 by a yoke 25 having an adjustable connection at 26 with the rod in order to permit variation of the effective length of the rod with relation to the tube 15. The elevation of members 14 and 15 is variable by providing the supporting web 17a with a vertical series of spaced holes 27 into which bolts 23 and 24 may be inserted. The outer end of tube 15 is threaded at 28 into the hollow casting 16, to the sides of which the forked branches 14a and 14b of member 14 are pivotally connected as at 29.

The casting 16 and the upper portion of tube 15 above the water level therein communicate with the steam chamber of the boiler by a pipe or flexible conduit 30, such as copper tubing, connected at 31 with the upper gauge glass fitting 32, which in turn is connected by pipe 20 with the boiler steam chamber. Thus with tube 15 communicating at its lower end with the water space in the boiler through pipe 18, and at its upper end with the boiler steam chamber through pipe 30, the level at which the water stands in the tube will normally correspond with the water level L in the boiler, and during normal or relatively slow changes in the boiler water level, the two levels will vary correspondingly and almost simultaneously. A suitable signaling device may be employed in association with the regulator to indicate abnormally high or dangerously low water levels in the boiler. For example, I may employ a signaling system, generally indicated at 33, comprising a steam whistle 34 operatively connected through a linkage generally indicated at 35 with lug 16a on casting 16, so as to blow when predetermined high and low water levels occur. The signaling device comprises no part of the present invention, and further details concerning it may be had from my copending application referred to above.

Being connected with the steam chamber, the upper portion of tube 15 above the liquid level therein is heated to a higher temperature than the lower portion of the tube, since the latter is cooled below the boiler water temperature due to heat radiation from the tube. It follows that as the water level rises or falls, the tube longitudinally contracts or expands by reason of the exposure of a lesser length of the tube to the steam temperature and a greater length to the

water temperature when the water level rises, or conversely when the water level drops. The length of rod 14 remaining fixed, longitudinal contraction or expansion of the tube 15 produces lateral (vertical) movement of the interconnected ends of the members, the extent of such movement being determined by various factors including the degree of contraction or expansion of the tube, length of the members, and their angularity. The casting 16 is operatively connected to the feed water control valve 11 by an adjustable length push rod 36 attached at its upper end to the casting lug 37 and at its lower end to the valve operating lever 38.

Assuming the boiler water level to rise above normal, the accompanying rise of the water level L in tube 15 causes the latter to contract longitudinally, and the resulting downward deflection of the interconnected end of the members depresses rod 36 to close the valve 11 and restrict the feed supply until the boiler water level drops to normal. Conversely, when the boiler water level falls below normal, the exposure of an increasing length of the tube 15 to the steam temperature causes the tube to expand and rod 36 to be moved upwardly to open the valve 11 and increase the rate of feed water supply.

Further as regards the expandible tube 15, it may be desirable to increase the normal temperature differential between the upper and lower portions of the tube exposed to steam and water, respectively, and ultimately to increase the responsiveness or sensitivity of the tube to relatively small changes in the water level. This object is accomplished by abnormally increasing heat radiation from the water-containing portion of the tube, as by providing the latter with a series of annular fins 39 extending from the casting 22 at least a substantial length of the tube below the normal water level. The annularly formed fins 39 afford greatly increased heat radiating surface area, and permit free expansion or contraction of the finned portion of the tube without interference by or distortion of the fins.

The feed water control valve 11 may of course be of any suitable form, and is shown typically as comprising a body 40 having an inlet 41, an outlet 42 and a valve 43 movable vertically with relation to its seat 44 by stem 45. Leakage from the valve body along the stem is prevented by a tubular sleeve 50 of rubber or other similar material, clamped at its upper end between the interior shoulder 46 of bushing 47 and the lower wedge-shaped end of an insert 48 that is pressed against the tube by tightening nut 49. The lower end of sleeve 50 has a fluid-tight connection with the stem 45 by way of a hollow nut 51 threaded at 52 on the stem and pressing the sleeve against a wedge-shaped annulus 53 carried by the stem. The stem is pivotally attached at 54 to lever 38 which in turn is mounted on the valve body by link 55 and bracket 56.

Provision is made for controllably applying cooling liquid to the upper portion of the regulator tube 15 through a flexible pipe, such as copper tubing 57, connecting at 58 into one side of the casting 16, as illustrated in Fig. 3. Preferably the cooling fluid used is boiler feed water taken from the supply line at the inlet side of the valve 43, as by way of line 59 tapped at 60 into the lower portion of the valve body. The cooling water flows from line 59 to line 61 containing a suitable filter 62 within which the water is freed of any solids, and if desired, chemically

treated for the removal of any corrosion and scale forming compounds. The filter periodically may be cleansed and freed of clogging bodies simply by closing valve 63, opening valve 64 in the blow-off line 65, and reversing the flow through line 61 and the filter 62.

The supply of water through line 61 and pipe 57 to the upper end of tube 15 preferably is rendered controllably variable in accordance with the operation of the feed water control valve 11, and therefore in accordance with variations of the water level in the boiler, by a suitable valve device 66 in line 61 and operated by a connection with the valve stem 45. The device 66 typically may comprise a tubular body 67 having a threaded neck 68 supported on the bracket 69, and containing a slide valve 70 having a downwardly extending stem 71 attached to stem 45 by the adjustable connection 72. Leakage of water from the valve body about stem 71 is prevented by a flexible rubber sleeve 73 maintained in spaced relation to the stem by the coil spring 74, and having its upper end fitted about an enlargement 75 and held in place by a wire 76. The lower end of sleeve 73 is pressed against the internal body flange 77 by a wedge sleeve 78 held in position by bushing 79 threaded into the lower end of the body. The valve proper comprises an annularly tapered portion 80 normally positioned opposite the inlet and outlet ports 81 and 82, and having relatively slight angularity, the illustrated taper being somewhat exaggerated for clarity of illustration. As will be apparent, opening movement of the valve 43 closes the slide valve 80 to restrict the flow of water through line 61 to the regulator tube, while closing movement of valve 43 increases the water supply to the tube.

Figs. 4 and 5 illustrate variational ways of applying cooling fluid to the upper portion of the tube, other than by injection into the casting 16. In Fig. 4 the cooling water from line 57 is shown to be applied to the exterior of the tube 15 by delivery into the upper end of a jacket 82 threaded at 83 on the end casting, and having its lower end suitably packed at 84 about the tube to accommodate differential expansion and contraction of the tube and jacket. From jacket 82 the water may be discharged through pipe 85 and passed to the boiler through a line 86 connecting therewith, or the water may be discharged to a sump or the like through line 87.

In accordance with the second variational form shown in Fig. 5, the water is discharged from pipe 57 into a tube or nozzle 58 extending through the casting 16' into the tube 15. The nozzle extends through a packing gland 88 which prevents leakage of steam from casting 16' along the nozzle. As illustrated, the nozzle may be provided with apertures 89 along its length so that the water discharged from the nozzle through the apertures may be directed against the sides and top, as well as the bottom of the regulator tube.

Considering now the operation of the regulator, it will be understood that preferably, valve 66 will permit a continuous flow of cooling water through pipe 57 to the controller tube 15. This flow of cooling water is of course extremely small in comparison to the feed water flow, being in the order for example of $\frac{1}{2}$ to $1\frac{1}{2}$ pints, more or less, per minute. During a sudden rise in the boiler water level, the accompanying surge in tube 15 tends to cool the tube and to cause its outer end to deflect downward to close the feed

water valve 43. Closing movement of the valve, however, opens valve 70 to increase the flow of cooling water to the tube 15, causing the water in the tube to be changed at more rapid rate, and thus preventing the tube from becoming excessively heated to the extent of destroying its sensitivity. As the boiler water level lowers, the resultant heating of tube 15 opens the feed valve 43 and progressively closes valve 70, the two valves thus working together and in compensating relationship. Similarly, when the water level drops and a greater length of the controller tube is exposed to the stream, resultant expansion of the tube opens the feed valve 43 and moves valve 70 in a closing direction to restrict the stream of cooling fluid. Consequently the lower the water runs down the tube 15, the greater the heating effect is had by diminishing the stream of cooling water. These cumulative effects thus make it virtually impossible for the boiler water to reach a low level if the feed pump is operating and has an available supply.

The maintenance of constant flow of water through the control tube eliminates a principal objection to the usual thermostatic tube, in that the tube now is stabilized in its action, and is made less sensitive to weather conditions by keeping its temperature more uniform except when there is a change in water level. Also, constant flow of water through the tube prevents the collection of sludge and renders frequent cleaning of the tube unnecessary.

I claim:

1. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber; means operated by longitudinal expansion and contraction of said tube for supplying liquid to said chamber, and means for passing liquid that is considerably cooler than the liquid in said chamber, in contact with the upper portion of said tube and into the chamber-contained liquid, to controllably reduce the normal rate of variation in the length of said tube resulting from liquid level changes in said chamber.

2. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber, and means for continuously passing a cooling fluid along and in contact with the upper portion of said tube to cool the tube and reduce its normal rate of variation in length resulting from liquid level changes in said chamber, said cooling fluid flowing from the tube into the liquid in said chamber.

3. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by

longitudinal expansion and contraction of said tube for supplying liquid to said chamber, and means for controllably applying cooling fluid to the upper portion of said tube above the liquid level therein to reduce the normal rate of variation in length of the tube resulting from sudden liquid level changes in said chamber.

4. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber, and means for controllably cooling the upper portion of said tube by a lower temperature liquid introduced into the tube.

5. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber, and means for variably cooling the upper portion of said tube by continuously applying thereto a lower temperature liquid flowing at a rate varying in accordance with liquid level changes in said chamber and passing into the water in said chamber.

6. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber, and means for cooling the upper portion of said tube by a lower temperature liquid discharged into the tube, and valve means for controlling such discharge of the liquid into the tube.

7. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and contraction of said tube, means for continuously applying cooling fluid to the upper portion of said tube, and means operated by said valve for controlling such application of cooling fluid to the tube.

8. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and con-

traction of said tube, means for introducing cooling fluid into the upper interior of said tube above the liquid level therein, and means operated by said valve for controlling such introduction of fluid to the tube.

9. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and contraction of said tube, means for delivering cooling liquid from the supply line at the inlet side of said valve to said tube, and means operated by said valve for controlling the delivery of said cooling liquid to the tube.

10. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and contraction of said tube, means for applying cooling fluid to the upper portion of said tube so that the cooling fluid flows into the liquid in said chamber, and a valve connected to the first mentioned valve and controlling such application of cooling fluid to the tube.

11. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and contraction of said tube, a stem for said valve, a pipe for delivering cooling liquid from the supply line at the inlet side of said valve into the upper end of said tube, and a control valve connected to and aligned with the stem of the first mentioned valve and controlling such delivery of cooling liquid to the tube.

12. Apparatus for controlling the level of heated liquid contained in a chamber having a vapor space above the liquid level therein, comprising an inclined tube, means connecting the tube with the liquid and vapor spaces in said chamber so that liquid stands in the tube inter-

mediate its ends and surges therein in accordance with liquid level changes in the chamber, means operated by longitudinal expansion and contraction of said tube for supplying liquid to said chamber, means for continuously discharging cooling liquid into the upper portion of said tube, and means for controllably varying the rate of such discharge in accordance with changes in the liquid level in said chamber.

13. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, a feed liquid supply line connected to said chamber, a valve in said line operated by longitudinal expansion and contraction of said tube, a pipe for delivering cooling liquid from the supply line at the inlet side of said valve into the upper end of said tube, and a control valve connected to the first mentioned valve and controlling such delivery of cooling liquid to the tube, said control valve normally passing a stream of the cooling liquid and operating to increase that stream when the liquid level in said chamber rises, and to decrease said stream when said liquid level falls.

14. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber and means independent of said connecting means for applying cooling liquid to the upper exterior portion of said tube above the normal liquid level therein and for conducting the cooling fluid into the liquid in said chamber.

15. Apparatus for controlling the level of heated liquid contained in a chamber having a vapor space above the liquid level therein, comprising an inclined tube, means connecting the tube with the liquid and vapor spaces in said chamber so that liquid stands in the tube intermediate its ends and surges therein in accordance with liquid level changes in the chamber, means operated by longitudinal expansion and contraction of said tube for supplying liquid to said chamber, and means independent of said connecting means for introducing cooling liquid into said tube above the normal liquid level therein.

JULIAN A. CAMPBELL.
